UNITED STATES PATENT OFFICE.

CHARLES WESLEY EVANS, OF LONDON, ENGLAND.

TREE OR STRETCHER FOR BOOTS AND SHOES.

No. 844,786.

Specification of Letters Patent.

Patented Feb. 19, 1907.

Application filed May 16, 1906. Serial No. 317,056.

To all whom it may concern:

Be it known that I, CHARLES WESLEY EVANS, a subject of the King of Great Britain, residing at London, England, have invented certain new and useful Improvements in Trees or Stretchers for Boots and Shoes and of which the following is a specification.

This invention has for its object to provide an improved construction of boot tree or stretcher, hereinafter termed "stretcher," of that class in which the stretcher is mechanically expanded both in the direction of its length as well as in the direction of its width by the operation of a single operating member. In this class of boot-stretcher mechanism has been heretofore provided by the operation of which the heel portion of the stretcher was caused to travel to the heel end of the boot, and when it contacted therewith the resistance to further lengthwise movement has caused the operating-screw which has produced the motion to then act to separate the two members of a toe portion, which toe portion was divided longitudinally into two parts. In this arrangement, however, the two toe portions were hinged together, so that when expanded they were turned about such hinge so that the angle between the two toe-pieces was increased, and consequently the said toe-pieces were not expanded in a way to enable them to adapt themselves to the shape or contour of the boot or shoe, and therefore that such an unnatural shape is given to the toe of the boot being stretched. Now my present invention refers to this class of boot-stretcher, but is directed to providing a construction whereby the toe-pieces when forced out shall accommodate themselves to the natural contour of the toe of the boot, and to this end each toe portion is made so that it is free to rock about a pin while it is forced outward laterally, and therefore is enabled to accommodate itself to the shape of the boot.

My invention therefore consists in the combination and arrangement of the parts by which the end in view is attained.

In order that my invention may be fully understood, I will describe the same with reference to the accompanying drawings, whereon—

Figure 1 is a vertical sectional elevation of my improved tree or stretcher, showing the stretcher with its parts in those relative

positions which they would occupy when introduced into the boot and before any expansion of the stretcher has been effected, Fig. 2 being an inverted plan view of the 60 stretcher shown at Fig. 1. Fig. 3 shows the stretcher on a smaller scale with the heel part in the position it would be caused to occupy when the stretcher was about to be inserted into the boot. Fig. 4 is a view 65 similar to that shown at Fig. 1, but illustrating the parts in their expanded positions; and Fig. 5 is an inverted plan view of the front part of the stretcher shown at Fig. 4 with the toe parts expanded. Fig. 6 70 is a side elevation, and Fig. 7 an end view, of a lever forming part of the mechanism detached.

For the purpose of this description the stretcher may be said to consist of three 75 main parts—viz., a body part 1, a heel part 2, and two toe parts 3 4.

The rear part of the body 1 is formed with a concave curved surface at 5, the heel part 2 being curved approximately to correspond at its forward surface, which surface normally contacts with the curved surface 5 of the body 1, and at the upper end the body has a bracket 6, formed with a slot or hole to receive a metal guide-rail 7, fixed 85 to the forward face of the heel part 2. Thus the said heel part 2 can be slid upward relatively to the body 1, as shown at Fig. 3, to permit of the insertion of the latter into the boot, and then the heel part 2 can be 90 slid or forced downward until it occupies its proper position, as shown in Fig. 1, in the boot, and so the stretcher can be easily inserted.

The forward end of the body part 1 is cut 95 away on each side (see Figs. 2 and 5) to receive the toe parts 3 4, which fit therewith, and so when the parts are in contact with each other they form together a complete tree, as at Fig. 2.

Each of the toe parts 3 4 has an inwardly-extending bracket 8, carrying a downwardly-extending pin 9 at its inner end, which enters an inclined slot 10 in a sliding plate 11, which is fitted and carried within the forward part 105 of the body portion 1 and is held in place by a cover-plate 12, which is fixed to the under side or sole of the body 1.

The pins 9, extending from the brackets 8, not only pass through the inclined slots 10 in the sliding plate 11, but also each pin 9 passes through a slot 13 in the cover-plate 12, such

slots 13 extending at right angles to the length of the stretcher, so that upon the sliding plate 11 being moved forwardly or rearwardly its inclined slots 10 act upon the pins 9 and cause the said pins to be distanced apart or drawn together and guided in their motion by the slots 13 in the cover-plate 12, so that the said pins are forced outwardly or retracted in the direction substantially at right angles to the length of the body part, while at the same time the toe parts from which the pins are carried are able to rock about the axes of the pins, and to thus accommodate themselves to the contour of the toe of the boot 15 into which the apparatus is inserted.

The rear end of the sliding plate 11 is pivoted at 14 to one end of a connecting-rod 15, the other end of which extends into a groove or recess 16, formed in the rear of the body part 1, and is there pivoted to a nut 17, which nut is engaged by a screw-threaded spindle 18, extending downward, passing loosely and freely through a hole in the bracket 6 and fitted at its upper end with an operating-handle 19.

The lower end of the screw-spindle, the latter forming the single member by the manual operation of which the expansion of the stretcher in both directions is effected, is 30 shouldered at its lower end and engages in the slotted end of one arm of a lever 20, which is pivoted at 21 between the walls of the slot or recess of the body part 1, and the other arm of the lever 20 is in a position to 35 act against the heel part 2 to force the latter outward and rearward away from the body part. The lever 20 is shown detached at Figs. 6 and 7 and is formed with a keyhole-shaped slot 22, so that the shouldered lower end 40 of the screw can be inserted at the larger end of the slot and moved to the smaller end.

Rearward of the guide-rail 7 and near the upper end of same the heel part 2 is recessed at 24, so that when the heel part is forced 45 down from the position shown at Fig. 3 to that shown at Fig. 1 the rear end of the bracket 6 will enter the recess 24 (because the slot in the bracket through which the rail 7 passes allows of some play) and prevent the 50 heel part 2 rising relatively to the body part 1, when the lever 20 commences its extension movement.

It will now be understood that when the stretcher is to be inserted into a boot its parts 55 are placed in the position shown at Fig. 3, and when inserted the heel part 2 is pressed downward until it assumes the position shown at Fig. 1. Then by operating the motor-screw 18 the end of the lever 20 engaging the 60 shouldered portion of the screw will be distanced from the nut 17, the effect being either to force rearward the heel part 2, and so lengthen the stretcher, or to separate the toe parts 3 4, or to effect both of these operations simultaneously. Thus, for example,

if the length of the stretcher is increased to the length of the boot and then encounters resistance to further expansion in that direction the further effort of the mechanism will be directed to effect the sidewise expansion 70 of the toe parts 3 4 by drawing rearward the sliding plate 11 by means of the connecting-rod 15. If, on the other hand, during the expansion of the stretcher the toe parts first encounter resistance to further expansion the 75 operative effect of the mechanism will be devoted to forcing rearward the heel part until it encounters a resistance equal to that of the toe portions, and then any further efforts of the mechanism due to the continued operation of the handle 19 will take effect both in the longitudinal and transverse directions. A reverse movement of the motor-screw 18 will retract the movable parts, and the stretcher can be easily extracted from the boot, as will 80 be well understood.

Obviously the body part 1 need not extend between the separable toe parts 3 4; but the separable toe parts themselves alone may compose the toe of the stretcher, the guides, 90 such as the cover-plate 12, extending from the body part 1, being carried in recesses or the like in the toe parts, as will be well understood.

What I claim as my invention, and desire 95 to secure by Patent, is—

1. In stretchers for shoes; the combination with a body part having a groove formed in its rear end extending from the upper to the lower part of said body, an operating-screw 100 freely located in said groove, a separate heel part, a two-armed lever pivoted in the groove of the body part one arm engaging the aforesaid operating-screw while the other arm is adapted to force the heel part rearwardly, a 105 forward extension of the body having slots extending in the direction of the width of the stretcher, and two toe parts adapted to have movement in the direction of the width, an inward extension on each toe part, and a 110 pin proceeding from each extension entering the slots in the extension of the body part, a nut on the operating-screw, and mechanism connected with the nut for distancing the toe parts substantially as set forth. 115

2. In stretchers for shoes; the combination with a body part having a groove formed in its rear end extending from the upper to the lower part of said body, an operating-screw 120 freely located in said groove, a separate heel part, a two-armed lever pivoted in the groove of the body part one arm engaging the aforesaid operating-screw while the other arm is adapted to force the heel part rearwardly, a 125 forward extension of the body having slots extending in the direction of the width of the stretcher, and two toe parts adapted to have movement in the direction of the width, an inward extension on each toe part, and a pin proceeding from each extension entering the 130

slots in the extension of the body part, a plate having angularly-diverging slots into which the pins of the toe parts enter, said plate being located above the forward extension of the body part and capable of sliding thereon, a nut on the operating-screw, and a connecting-rod between the nut and the angularly-slotted sliding plate substantially as set forth.

- 10 3. In stretchers for shoes; the combination with a body part having a concave rearward surface and a groove formed in said rear surface extending from the upper to the lower part of said body, a heel part having a forwardly-curved front surface and a notch formed near the upper end thereof, a bracket extending rearward from the upper part of the body and having a slot in its rearward extension, and a rail on the heel part extending 15 through said slot to permit of the heel part being slid downward into the shoe after the insertion of the body part and retained in position by the bracket entering the notch; of an operating-screw extending into the 20 body part, two toe parts adapted to have movement in the direction of the width, a forward extension of the body part for guiding the said toe parts in their movements, and mechanism operated by the aforesaid 25 screw for extending the heel and toe parts by balanced motions in the directions of the length and width substantially as set forth.
- 30 4. In stretchers for shoes; the combination with a body part having a concave rearward surface and a groove formed in said rear sur-

face extending from the upper to the lower part of said body, a heel part having a forwardly-curved front surface and a notch formed near the upper end thereof, a bracket extending rearward from the upper part of the body and having a slot in its rearward extension, and a rail on the heel part extending through said slot to permit of the heel part being slid downward into the shoe after the insertion of the body part and retained in position by the bracket entering the notch; of an operating-screw freely located in the rear groove of the body part, a two-armed lever pivoted in the groove of the body part near the lower end thereof one arm 40 engaging between fixed collars on the spindle of the operating-screw while the other arm is adapted to force the heel part rearwardly, two toe parts adapted to have motion in the direction of the width, a lower forward extension of the body for supporting the toe parts and having guides for guiding the latter during their expansion movements, a plate having angularly-diverging slots located 45 above the forward extension of the body part 40 and capable of sliding thereon, a nut on the operating-screw, and a connecting-rod between the nut and the angularly-slotted plate substantially as set forth.

In witness whereof I have hereunto set my 50 hand in the presence of two witnesses.

CHARLES WESLEY EVANS.
